ANTHONY P. HINSKY, OF BROOKLYN, NEW YORK.

COUPLER FOR RADIO.

Application filed June 25, 1925. Serial No. 39,615.

This invention relates to a coupler for radio circuits. An object of the invention is to provide a simple and efficient coupler which in its operation permits finer tuning, more stable operation, and economy of manufacture, which reduces the cost a considerable amount.

The invention is illustrated in the drawings, of which—

10 Figure 1 is a perspective view of the coupler;

Fig. 2 is a section on the line 2—2 of Fig. 1; and

15 Fig. 3 is a diagrammatic representation of the way in which the coils are disposed and connected.

The form of the invention shown in the drawings is a preferred form, although it is understood that modifications in the construction and arrangement of the parts and in the character of the materials used may be adopted without departing from the spirit of the invention as set forth in the appended claims.

20 This invention in its general aspect comprises a primary and a secondary, the secondary preferably being rotatable. The primary is divided into two portions, preferably connected in series, one portion being fixed and the other portion being associated or mounted with the rotatable secondary so as to move therewith. In this manner it is found that a much finer tuning is possible, the coupling is more stable, and because of the construction hereinafter described the economy of manufacture is considerably enhanced.

In the preferred form of the invention shown in the drawings I have provided a bracket plate 10 which is made, preferably, of one piece of metal with pedestal portions 11 and 12 to form bearings for shafts 13 on which a secondary winding 14 is mounted, this secondary portion being of the basket-ball type and rotatable with the shaft. Mounted on insulating plates 15, one of which is shown in Fig. 1, are two ringlike primary coils 16 and 17 adapted in the normal position of the secondary shown in Fig.

1 to have a common axis with the secondary. 50 The primary windings 16 and 17, however, are spaced apart symmetrically with respect to the length of the common axis. This is particularly clearly shown in Fig. 2.

Disposed within the basket-ball secondary, and wound in a ringlike fashion similar to the coils 16 and 17, are two other primary windings 18 and 19 which, when the secondary is in its normal position shown in Fig. 2, occupying a plane coincident with the planes occupied respectively by the coils 16 and 17 and, therefore, have a common axis with the windings 16 and 17 and with the rotor 14. The windings 16, 17, 18 and 19 are, as shown in Fig. 3, connected in series; but the windings 18 and 19 are rotatable with the secondary 14, whereas the windings 16 and 17 are fixed. It will, therefore, be noticed that the rotatable primary coils 18 and 19 are similarly symmetrically disposed with relation to the common axis above mentioned.

The particular features and advantages of this coupler are as follows:—

(1) It relates to a coupler whereby the 75 full range of inductance is obtained by a 180° revolution.

(2) It incorporates a tight and loose inductive coupling.

(3) The construction as described requires a minimum amount of supporting material, thereby reducing losses.

(4) The rotor cuts the lines of the fixed primary at an even or uniform rate when revolved and still remains equidistant at all 85 times therefrom, thus permitting a very even adjustment.

(5) In this invention the rotor cuts the lines of the primary at various angles, whereas in other types the lines of the primary are cut at right angles.

What I claim is:—

1. A coupler for radio circuits, which comprises a rotatable secondary coil, a primary winding having a portion fixed and surrounding the secondary, another portion of the primary movably disposed with the secondary and supported within the secondary,

said movable portion of the primary being connected in series with the fixed portion of the primary.

2. A coupler for radio circuits, which comprises a basket-ball secondary, a pair of ringlike primary coils fixed in position around the secondary, said primary being spaced apart symmetrically with respect to the axis of the secondary so that the two

fixed primary coils and the secondary have 10 a common axis, another pair of primary coils being supported within the secondary, said second pair of primary coils being wound ringlike, said second pair of primary coils being movable with the secondary and 15 connected in series with the fixed pair of primary coils.

ANTHONY P. HINSKY.
